No. 125

Henry Biggins (assigned to J. G. Jackson)
Design for fire place Plate
Patented June 5th 1847

Design for Frame of fire place grate.
Henry Biggins, Assigned to J. G. Jackson,
New York.
1847.

Des. 125

Henry Biggins New York (after of James L Jackson)
New York, New York.

Letter Patent Design No. 125, dated 5th June 1847.

The schedule referred to in these Letter Patent and making
part of the same.

To all whom it may concern: Be it known that I, Henry Big-
gins of New York, in the County & State of New York have pro-
duced a new design of configuration of figures to be cast in metal,
and when combined to form "a frame of a fireplace Grate;" and I
do hereby declare that the following is a full, clear and exact de-
scription of the same, reference being had to the annexed drawing and

Dec. 125

king a part of this specification.

Bound the extreme outside, in rectangular form of three sides, is a free receding moulding (a, a, a). Immediately inside of this is a dead flat ground work, (b, b, b) continuing to the base, the width of this flat being varied on the inside by the several different figures. Inside at the centre is a piece of receding moulding (c) extending to matched scrolls, (d, d,) on each side, these matched scrolls (d, d) being on convex curve towards the centre, and match with the terminating scrolls (f, f) at both corners. Immediately inside the last named scrolls commencing at the centre, in a concave scroll and extending to the corners is a set of finishing scroll and leafage work (g, g, g) terminating the top of the frame. The two sides are quite alike, inside of the flat and below the above described terminating scrolls, will be seen a kind of prick'd ground work, upon which are raised a set of leafage scrolls (h, h, h) to the bottom or base, and inside of these, and near by the same, some shell work (i, i) and dropping therefore a set of leafage scrolls to the base. The whole being a centre receding "Grate frame".

What I claim as my production is this peculiar combination a combination of figures so as to form a "frame of a fire place Grate", to be cast in metal the same being as substantially set forth herein.
